Hilys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,103.

Specification of Letters Patent.

Patented Aug. 9, 1921.

Application filed January 16, 1920. Serial No. 351,769.

To all whom it may concern:

Be it known that I, FRED S. CARR, a citizen of the United States, and a resident of Newton, in the county of Middlesex and 5 Commonwealth of Massachusetts, have invented an Improvement in Separable Fasteners, of which the following description, in connection with the accompanying drawings, is a specification, like characters on the 10 drawings representing like parts.

This invention pertains to improvements in separable fasteners, and more particularly, though not exclusively, to separable fasteners of the three-side lot type particularly well adapted for use in connection 15 with the fastening of automobile curtains and the like.

It is among the objects of the invention to provide a stud and socket fastener of simple 20 construction wherein the strain between the stud and socket shall normally be taken by unyielding engaging parts while the stud and socket are resiliently held in engagement. Other objects of my invention will 25 be described later in the specification.

Referring to the drawings, wherein I have elected to show a preferred form of one 25 illustrative embodiment of my invention:—

Figure 1 is a front elevation of a portion 30 of a preferred form of my invention;

Fig. 2 is a longitudinal section, partly in elevation, on the line 2—2 of Fig. 1;

Fig. 3 is an elevation, partly in section, on the line 3—3 of Fig. 2; and

Fig. 4 is a section, partly in elevation, on the line 4—4 of Fig. 2.

Referring to the drawings and the preferred embodiment of my invention selected for illustrative purposes, I have shown a 40 fastener including a stud having a head 5, a neck 6, and a shank portion 7 coöperating with a socket including a fixed and unyielding jaw element 8 adapted to engage with the neck 6 of the stud, a spring jaw element 9 also adapted to engage the neck of the 45 stud, and a strain-receiving shank-engaging portion 10 opposite the fixed jaw portion 8.

The socket preferably includes, as shown, a jaw-containing casing 11 and a coöperating 50 socket-inclosing plate 12 which preferably carries the fixed jaw 8. The stud-engaging edge of the jaw 8 is preferably rounded, as shown, substantially to conform to the shoulder on the stud between the neck 6 and the 55 head 5.

The socket may be secured to the curtain 13 by a clench plate 14, which is preferably provided with an elongated opening to permit tipping of the socket relative to the stud in one direction only. 60

The fastener herein disclosed resembles somewhat those shown in my issued patents, numbered 1,278,798 and 1,278,799, but differs therefrom in several respects which materially contribute to the smooth and certain 65 operation of the device.

For instance, the rounding of the fixed jaw 8 at its edge not only provides greater conformity between the fixed jaw and the shoulder on the stud, but facilitates separation of stud and socket by permitting a smooth sliding action when the stud and socket are tipped one relative to the other in the direction shown by the arrow in Fig. 2. The rounding of this edge also to some extent renders smoother the action of engaging and disengaging the stud and socket. The shaping of the unyielding jaw element 8 to conform more nearly to the shape of the aperture through which the head of the 70 stud enters promotes facility of engagement and of disengagement when the parts are relatively tipped in the predetermined direction, and the improved shape of the stud 75 illustrated over that shown in the foregoing 80 patents also contributes to certainty of ease of operation. 85

The stud and socket parts shown in the present drawings are also adapted to oppose separation of stud and socket by pressure 90 inward on the upper portion of the socket such pressure in the present disclosure serving to wedge the parts more firmly together. This feature of my invention is claimed in a co-pending application filed herewith, 95 Serial No. 351,768.

While I have shown and described a preferred form of one embodiment of my invention, it will be understood that changes involving omission, substitution, alteration 100 and reversal of parts, and even changes in the mode of operation, may be made without departing from the scope of my invention, which is best defined in the following claims. 105

Claims:

1. A separable fastener comprising, in combination, a stud having a head and a neck, a socket providing a stud-receiving aperture therein having at one side thereof a 110

fixed jaw for engagement with the neck of the stud, and on the other side thereof resilient means for pressing the neck of the stud into engagement with said fixed jaw, 5 the shoulder between the neck of the stud and the head thereof being inclined, and the neck-engaging face of the fixed jaw being rounded in longitudinal section.

2. A separable fastener comprising, in combination, a stud having a head and a neck with a sloping shoulder between them, said stud coöperating with a socket having a stud-receiving aperture and providing a fixed jaw having a marginal portion curved 15 in a direction transverse to the general plane of the socket, said stud and socket separable

by relative tipping movement about said fixed jaw as a fulcrum.

3. A separable fastener comprising, in combination, a stud having a head and a neck, coöperating with a socket having a stud-receiving aperture and providing a fixed jaw providing a marginal portion curved substantially to conform to the curve of the stud-receiving aperture, the marginal portion of said jaw also being curved in another dimension substantially to conform to the slope of the shoulder between the head and the neck of the stud.

In testimony whereof, I have signed my name to this specification.

FRED S. CARR.
